UNITED STATES PATENT OFFICE

CHARLES E. HALEY, OF CANTON, OHIO

CANDLE HOLDER

Application filed October 29, 1931. Serial No. 571,906.

The invention relates to holders for candles for use with candlesticks, candelabra, and the like.

The invention has for its principal object 5 the provision of means for securely holding candles erect in candlesticks, candelabra, etc., to make the use of candles more ornamental by assuring that they will always be erect in the candlestick or candelabrum and eliminate the dirt and muss incident to the use 10 of candles when they do not accurately fit the socket in the candlestick or candelabrum permitting the candle to lean sidewise spilling the grease and burnt wick therefrom, and also to avoid the danger of fire occasioned 15 by illfitting candles that fall from their supports or from burning paper or other fabric used to wrap the bases or butts of the candles to tightly fit them in their supports. 20 A further object of the invention is the provision of a holder for securing candles in their supports on candlesticks or candelabra having a tapered plug of yielding material that is tapered so as to provide for fitting 25 sockets in the supports, of varying diameters, and securing to said plugs a supporting member including a disk secured to the plug having spaced prongs around its edge that incline outwardly to provide means for securely engaging the bases or butts of candles of varying diameters and hold them securely positioned in between the prongs. The invention also includes a circular drip 30 plate or bobache that is mounted between the plug and disk to catch the drip of grease and burnt wick from the candle, and a drapery hanger including a plurality of radial arms having hooked ends to engage draperies or other decorations and which may also be used to support a shade or globe. 35

The invention will be described in detail hereinafter and will be found illustrated in the accompanying drawing in which

40 Figure 1 is a fragmentary view of a conventional candlestick or candelabrum showing the candle holder in position therein;

Figure 2 is a similar view partly in section;

50 Figure 3 is a top plan view;

Figure 4 is a top plan view of the candle clamping device.

Figure 5 is an elevational side view of the candle clamping device;

Figure 6 is a plan view of the drapery 55 hanger; and

Figure 7 is a fragmentary view partly in section of another type of candlestick or candelabrum showing the candle holder in position, the drapery hanger being omitted, 60 and the drip plate or bobache only being shown in section.

In the drawing similar reference characters are used to designate corresponding parts 65 in all of the views.

In Figures 1 and 2 is shown one type of conventional candlestick or candelabrum A, and in Figure 7 another type A' is shown. The candlestick or candelabrum A is provided with a candle socket a, a' indicating the socket 70 in the device shown in Figure 7.

The candle holder as shown in the drawing includes a plug member 10 that is preferably made of yielding material such as cork, rubber or the like and tapered as shown at 11 and 12, respectively, the tapered portion 11 being on a greater angle than the portion 12, this structure and material insuring a secure engagement of the plug member in the socket of the candlestick or candelabrum. Plug 75 member 10 is also provided with a socket or recess 13 opening through its bottom, this structure also contributing to the adjustability of the member to fit the candle socket, and providing means for securing a screw or threaded bolt 14 through the upper portion of the plug. 80

The candle clamping means includes a circular plate 15 having an opening 16 to receive the bolt or screw 14, and is provided with a plurality of spaced prongs 17 extending upwardly therefrom and inclined outwardly as shown in the drawing so as to accommodate the device to hold candles of 85 varying diameters as shown at B, B', in Figures 1 and 2, and C, C', in Figure 7. Each of the prongs 17 is transversely curved exteriorly and V-shaped interiorly as shown to provide cutting edges 18 that will cut into the 90 100

base of the candle to securely hold it engaged.

A concaved drip plate or bobache 19 is provided and has a downturned marginal rigidifying rim or flange 20, and a central opening 21 to receive the bolt or screw 14. The drip plate is mounted between the plug 10 and the plate 15 as shown in Figures 1, 2 and 7 and is designed to catch the drip from the candle, including the unconsumed wax or other material and the charred wick.

A hanger or holder may also be provided and consists of a central disk member 22 having integral outwardly extended and spaced arms 23 with their extremities formed with V-shaped hooks 24. The V-shaped hooks are adapted to support drapery when the candlestick or candelabra is used for a church altar decoration, and is also adapted to support a shade or globe. As shown in Figures 1 and 2 the hanger or holder is adapted to be sup-

ported between the plug 10 and drip plate 19, the disk 22 being provided with an opening 25 to receive the screw 14.

I claim:

A candle holder, comprising a plug member adapted for insertion in the socket of a candlestick and the like, a disk removably secured to said plug, a plurality of upwardly extending and outwardly inclined prongs on said disk, each of said prongs having a longitudinal V-shaped-groove therein providing cutting edges at the two side edges of the prong to cut into the base of a candle to hold it erect, the inclination of the prongs providing for support of candles of varying diameters, a concaved drip plate, and a downturned marginal flange on the edge of said plate to rigidify it.

In testimony whereof I affix my signature.

CHARLES E. HALEY.
